UNITED STATES PATENT OFFICE.

STEPHEN D. JONES, OF BLUE ISLAND, ILLINOIS.

IMPROVEMENT IN LIFTING-JACKS.

Specification forming part of Letters Patent No. 118,020, dated August 15, 1871.

To all whom it may concern:

Be it known that I, STEPHEN D. JONES, of Blue Island, in the county of Cook and State of Illinois, have invented a new and useful Improvement in Lifting-Jacks; and I do declare that the following is a true and accurate description thereof, reference being had to the accompanying drawing and to the letters of reference marked thereon, and being a part of this specification, in which—

Figure 1 is a side elevation of my invention, and Fig. 2 a horizontal section on the line $x x$ of Fig. 1.

Like letters of reference made use of in the several figures indicate like parts.

To enable those skilled in the art to make and use my invention, I will proceed to describe the same with particularity, making use in so doing of the aforesaid drawing.

A is an upright standard supported by a base or platform, B, which, if desired, may be mounted upon small wheels or casters for convenience in moving about. C is a movable or sliding fulcrum placed in front of the standard, and connected thereto by a fixed clamp or slide, d, clasping into the vertical grooves D, one upon each side of the standard. A bail-shaped pawl, E, is pivoted to the standard at the point e, and surrounds the fulcrum C and engages with its ratchet

or notched face F, furnishing a means whereby the fulcrum may be adjusted to any desired height within the limit of the mechanism to suit various sized vehicles or other objects to be lifted. G is a lever, mortised, as indicated by dotted lines, to fit over the standard and fulcrum, and pivoted to the fulcrum at g. This lever is fitted with a check-pawl, H, which engages with a ratchet, I, upon the rear face and upper extremity of the standard, and serves to hold the lever in position after the lift is made.

The lifting-jack so constructed affords a simple, cheap, and exceedingly durable device, capable of being adjusted to any sized vehicle without any detachment of its parts.

Having thus described my invention, what I claim, and desire to secure by Letters Patent, is—

The combination of the standard A having grooves D, the fulcrum C, clasps d, bail-shaped pawl E, ratchet F, lever G, pawl H, and ratchet I, all constructed and arranged substantially as described and shown.

S. D. JONES.
